Attorney

UNITED STATES PATENT OFFICE.

HANS SCHAFER, OF BERLIN, GERMANY.

SOUND REPRODUCER.

Application filed October 27, 1923. Serial No. 671,148.

REISSUED

To all whom it may concern:

Be it known that I, Dr. HANS SCHAFER, engineer, citizen of the German Republic, residing at Berlin, in the State of Prussia, 5 have invented certain new and useful Improvements in Sound Reproducers, of which the following is a specification.

This invention relates to sound reproducers and more particularly to diaphragm 10 mountings for telephone receivers, loud speakers and the like.

In devices of this character the diaphragm is usually disc shaped and is held around its periphery. A drawback of such devices is 15 that not the entire surface of the diaphragm is exposed to the air. Furthermore, during its movement the diaphragm produces objectionable noises because it is rigidly held around its periphery.

20 In accordance with the present invention these drawbacks are avoided by holding the diaphragm around its periphery in a manner that the diaphragm contacts only with some soft material preferably rubber and 25 that the whole surface of the diaphragm is exposed to the air. The diaphragm provided in accordance with the present invention moves practically freely in the air and substantially parallel with its normal position.

30 This will result in improving the quality and quantity of the reproduced sound.

The soft material e. g. rubber, used for holding the diaphragm is preferably stretched over the whole surface of the diaphragm or it may be solidly connected 35 therewith around its periphery. Due to the provision of such rubber pad the vibration of the diaphragm will be materially damped. Preferably, the diaphragm is cone-shaped 40 whereby the surface of the diaphragm is increased notwithstanding the fact that the cross section of the holding arrangement remains the same. One of the advantages of the diaphragm forming the object of the 45 present invention consists in that due to the provision of the soft material used for clamping the diaphragm the latter makes no contact with metal.

The drawings show a diaphragm constructed in accordance with the present invention, Fig. 1 being a sectional view, and 50 Fig. 2 a top plan view.

In the arrangement shown in the drawings a diaphragm 1 is made of a cone-shaped 55 sheet of aluminum or some other rigid ma-

terial which in any well known manner, e. g. through the agency of a rod 2, is caused to vibrate. The metallic cone is entirely covered with a piece of flat rubber 3 which projects beyond the periphery of the diaphragm. The projecting rubber rim 4 is wrapped around a ring 5 of resilient material and is forced therewith into a suitably shaped frame 6. The diaphragm 1 is attached to the rubber cover 3 by means of a 60 plurality of small rivets 7 provided around its periphery. The frame 6 is provided with projections 8 by means of which it may be attached to a table or panel. It will be seen from the drawings that the diaphragm 70 1 is nowhere in contact with metal, that it moves substantially parallel to its normal position, and that substantially the entire surface of the diaphragm is exposed to the air. The rubber coating will entirely eliminate the natural vibrations of the diaphragms. 75

Obviously, certain features of the invention may be practised with a flat diaphragm as well as a cone-shaped diaphragm. Instead of using rubber for covering the diaphragm some other soft substance may be used. Furthermore, two cone-shaped diaphragms like the one shown in the drawings 80 may be combined into a double cone. These 85 and other modifications as well as various applications of the invention to commercial structures will readily suggest themselves to those skilled in the art. 90

What is claimed is:

1. A sound reproducer comprising a vibratory diaphragm, a sheet of resilient material engaging and extending over one face of the diaphragm and beyond the periphery thereof, and a support encircling the diaphragm and of greater size than the diaphragm, said sheet adjacent its periphery being secured to said support. 95

2. A sound reproducer comprising a vibratory diaphragm, a sheet of resilient material engaging and extending over one face of the diaphragm, said sheet being affixed to the diaphragm adjacent the periphery of the diaphragm and extending beyond said periphery, and a support encircling the diaphragm and of greater size than said diaphragm, and means for engaging the sheet adjacent its periphery for affixing it to said support. 100 105

3. A sound reproducer comprising a vi- 110

bratory diaphragm, a sheet of resilient material engaging and extending over one face of said diaphragm, a clamping ring securing the sheet to the diaphragm adjacent the periphery, and a support encircling the periphery, and a support encircling the latter, said support having an annular recess and a fastening ring to press the periphery of the sheet into said recess to mount the diaphragm with the sheet upon said support.

⁵ beyond said periphery, a support of greater size than the diaphragm and encircling the

In testimony whereof I affix my signature.
DR. HANS SCHARF.
